Specification for Design.

Patented Oct. 8, 1912.

Application filed August 23, 1911. Serial No. 645,666. Term of patent 7 years.

To all whom it may concern:

Be it known that I, LINDSLEY SCHEPMOES, a citizen of the United States, residing at Hasbrouck Heights, county of Bergen, and State of New Jersey, have invented a new, original, and ornamental Design for Bracket-Lamp Fixtures, of which the following is a specification.

The nature of my design is fully illustrated in the accompanying drawing, to which reference is made, and in which—

Figure 1 represents a side elevation of the design; and Fig. 2 a front elevation thereof.

My design comprises a bracket of a

prismatic section horizontally disposed and provided at one end portion with a prismatic enlargement or knob from which projects a pendant, the periphery of which flares generally outwardly and away from the bracket, having the contour and relative proportion of parts shown.

I claim:

The ornamental design for a bracket lamp fixture as shown and described.

LINDSLEY SCHEPMOES.
